(57) **CLAIM**

The ornamental design for dust collecting hood as shown and described.

DESCRIPTION

FIG. 1 is a top front perspective view of a dust collecting hood showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIGS. 8 and 9 illustrate the dust collecting hood in use, where the dust collecting hood is assembled to a fluid sprayer and a suction tube of a vacuum cleaner; and,
FIGS. 10 and 11 illustrate that the dust collecting hood in use, where the dust collecting hood is assembled to another fluid sprayer and another suction tube of another vacuum cleaner.

The broken lines illustrate environmental structures which form no part of the claimed design.
